Horatio E. Bellows.
ATTORNEY

UNITED STATES PATENT OFFICE.

FRANK N. BOSS, OF CRANSTON, RHODE ISLAND.

ELECTRIC CANDLE.

Application filed April 11, 1925. Serial No. 22,282.

My invention relates to that type of electric candles wherein a shaft of relatively insulating material is made to resemble a candle body, and an incandescent electric light bulb, with suitable electrical connections, represents the candle flame.

The essential objects of my invention are the capability of facile assemblage, disassembly, and portability; security against fire; accessibility to the electric terminals; and simplicity and inexpensiveness of construction.

To the above ends essentially my invention consists in such parts and in such combinations of parts as fall within the scope of the appended claim.

In the accompanying drawings which form a part of this specification

Figure 1 is a vertical central section of my candle,

Figure 2, a side elevation of the lower portion of the same,

Figure 3, a section of the base of the latter on line 3-3 of Figure 2, and

Figures 4 and 5, transverse sections on lines 4-4 and 5-5 respectively of Figure 1.

Like reference characters indicate like parts throughout the views.

The body or shaft 8 of the candle is preferably of wood, porcelain, or other electrically insulating material comprising upper and lower tubular sections 9 and 10 respectively. The lower portion of the section 10 is integral with a tray 11 provided in its base 13 with horizontal parallel passages 14 extending from its exterior to an extended portion of the bore 15 of the candle body. In the bores 15 and 16 of the body sections 10 and 9 are frictionally or otherwise fixed internally threaded sleeves 18 and 19 respectively of vulcanized rubber or other insulating material.

A receiving plug or contact member 23 of rubber or other insulating material has a cylindrical body portion 24 fitted in the top of the bore 15, and a diametrically reduced externally threaded portion 25 adapted to engage the thread of the sleeve 18. In

two longitudinal openings 27 extending through the member 23 are fixed metallic tubular terminals 28, in the lower ends of which are engaged the exposed ends of insulated conductors 29 extending through the passages 14 to any convenient source of electrical current.

An entrant plug or contact member 33 has a hard rubber body portion 34 in the lower end of the bore 16, and a reduced exteriorly threaded end portion 35 engaging the sleeve 19. Longitudinal openings 37 through the member 33 have fixed therein metallic sleeves or tubular terminals 38 which receive the exposed ends of insulated electric wires or conductors 39. In the lower ends of the sleeves 38 are fixed the upper ends of metallic posts or contact members 40 having compressible bifurcated lower portions projecting downwardly to slidably enter the tubular terminals 28.

Fixed in the upper end of the bore 16 is a socket member 42 containing a screw threaded metallic cup 44 containing an insulating ring 45 to afford spaced insulated areas or contacts for attachment thereto of the upper ends of the wires 39. The cup 44 receives the threaded metallic base 49 of the electric lamp bulb 41.

I claim:—

In an article of the character described, a supporting tray having a tubular section rising therefrom, a second tubular section resting upon and supported by the first-named section, an electric light on the upper section, sleeves in the adjacent ends of the sections, a socket member of insulating material engaging the sleeve in the lower section, vertical tubular contacts enclosed in the socket member, an entrant member of insulating material engaging the sleeve in the upper section, depending metallic posts in the entrant member adapted to register in the tubular contacts, and electrically connected with the lamp.

In testimony whereof I have affixed my signature.

FRANK N. BOSS.
